UNITED STATES PATENT OFFICE.

SINCLAIR STUART, OF PLAINFIELD, NEW JERSEY.

CONSTRUCTION OF SHIPS.

SPECIFICATION forming part of Letters Patent No. 538,799, dated May 7, 1895.

Application filed December 17, 1894. Serial No. 532,034. (No model.)

To all whom it may concern:

Be it known that I, SINCLAIR STUART, of Plainfield, in the county of Union and State of New Jersey, have invented a new and useful Improvement in the Construction of Ships or other Vessels, of which the following is a specification.

This improvement relates to ships and other vessels constructed entirely of steel or iron or to what are known as composite vessels constructed partly of steel or iron and partly of wood. The construction which constitutes my said improvement is mainly distinguished from the construction heretofore common in that in the common construction the "frames" so called have the form of ribs running continuously outward from the keel through the bottom and thence upward through the exterior structure of the vessel, but according to my improvement the main frames are arranged lengthwise of the vessel and run continuously or without interruption throughout the whole or any portion of the length of the exterior structure thereof. By this arrangement of the frames and the combinations hereinafter described and claimed whereby the so arranged frames are braced, I am enabled to construct a vessel having greater longitudinal stiffness and strength with less weight of metal as compared with vessels heretofore constructed.

Figure 1 represents a transverse section of parts of one side and the bottom of a vessel embodying my invention. Fig. 2 represents a portion of the side of the vessel with the plating removed. Fig. 3 represents a horizontal section in the line 3 3 of Fig. 2.

Similar letters of reference designate corresponding parts in all the figures.

40 A A designate the main frames which run lengthwise of the vessel through the whole or any portion of the length of the exterior structure thereof and which may be united with the structure of the stem and stern in any suitable manner. These longitudinal frames are represented as having a transverse section of what is known as channel form, the web of the channel being arranged horizontally as shown in Fig. 1.

45 B B' are upright braces interposed at suitable intervals between the longitudinal frames A A. These braces are represented

as so arranged in alignment with each other (see Fig. 2) that they resemble ribs which are interrupted only where the longitudinal frames A A intervene. The said braces B B' are represented as made of two kinds of channel steel or channel iron, those B being of a width equal to that of the longitudinal channel frames A and those B' being much narrower. The said braces have the webs of their channels arranged crosswise of the vessel and their flanges parallel with the sides thereof as shown in Fig. 2 and all are so arranged that the plating C of the vessel may lie 65 against the outer flanges. The wider braces B are represented as less numerous than the narrower ones B', the wider and narrower ones being placed at regular intervals. The braces B are united with the longitudinal 70 frames A A by transversely arranged angle clips a a which are riveted to the said braces and frames above and below the latter; and the narrower braces B' have their inner flanges riveted to angle bars b b which are 75 riveted to the longitudinal frames A A. The said angle bars b are represented (see Figs. 2 and 3) as extending all the way between the wider braces B so that one of the said bars b serves for several of the said narrower braces 80 B'. The outer flanges of the several braces B B' are flush with the outer flanges of the longitudinal frames to receive the outer plating of the vessel.

85 D are the deck beams of the vessel represented as of channel form, riveted through their flanges directly to the webs of the said frames A by rivets c c as shown in Figs. 2 and 3 and also riveted through their own webs and to the webs of the wide braces B by rivets d d.

90 E are the margin strakes of the decks secured to the inner flanges of the longitudinal frames A by angle bars e which run parallel with the said frames and are riveted to the said frames and strakes.

95 F are bracket plates which are secured to the narrow braces B' by being riveted by rivets g directly to the webs of said braces. These bracket plates F are also fastened to the margin strakes E by angle bars h riveted to the said plates and strakes.

100 G are bracket plates arranged one below each deck beam D close to the webs of the wider braces B and riveted by rivets l directly

to the said webs. These plates G are also fastened to the lower flanges of the deck beams by angle bars *i* riveted to the said flanges.

5 H are bracket plates arranged one above each lower deck beam D and close to the webs of the wider braces B and riveted by rivets *j* directly to said webs. These bracket plates H are also fastened to the margin strakes and to the deck beams by angle irons *k* which are 10 riveted to the said plates and also riveted to the upper flanges of the deck beams through the margin strakes.

15 In carrying out this invention the bottom of the vessel may be constructed in any suitable manner. In the example represented the vessel has a water ballast bottom and is represented as constructed according to my United States Letters Patent No. 526,823, dated October 2, 1894, except that it has channel plates I running continuously through it 20 above the transverse floor channels J.

What I claim as my invention is—

1. In the exterior structure of a ship or other vessel, the combination of main frames A of 25 channel form arranged lengthwise of the vessel and running continuously throughout any portion of the length thereof with their webs

located horizontally, narrower upright channel braces B' and wider upright channel braces B interposed between and abutting 30 against said frames, transversely arranged angle clips *a* riveted to said frames A and to said wider braces B, and angle bars *b* which are arranged lengthwise of the vessel between said wider braces B and each of which is riveted to one of said frames A and to two or more of said narrower braces B', substantially as herein described.

2. In a ship or other vessel, the combination of main channel frames arranged lengthwise of 40 the vessel and running continuously through any portion of its length at the sides thereof, interrupted upright braces interposed between said frames and abutting against said frames, and deck beams of channel form riveted 45 through their own flanges to the webs of said channel frames and riveted through their own webs to the webs of said upright channel braces, substantially as herein set forth.

SINCLAIR STUART.
